UNITED STATES PATENT OFFICE

107,311

DESIGN FOR A TORQUE MEASURING WRENCH

Allen I. Dunn, Cedar Rapids, Iowa, assignor to
Cedar Rapids Engineering Company, Cedar
Rapids, Iowa, a corporation of Iowa

Application October 13, 1937, Serial No. 72,144

Term of patent 7 years

To all whom it may concern:

Be it known that I, Allen I. Dunn, a citizen of the United States, residing at Cedar Rapids, in the county of Linn and State of Iowa, have invented a new, original, and ornamental Design for A Torque Measuring Wrench, of which the following is a specification, reference being had to the accompanying drawing, forming part thereof.

Figure 1 is a bottom view of the wrench, showing my new design.

Figure 2 is a side elevational view of the wrench shown in Figure 1.

Figure 3 is a top plan view of the wrench shown in Figures 1 and 2.

I claim:

The ornamental design for a torque measuring wrench as shown.

ALLEN I. DUNN.
